UNITED STATES PATENT OFFICE

2,515,586

ANDIRON CONSTRUCTION

James J. Blockinger, Cuyahoga Falls, Ohio, assignor to The Galanot Products Company, Alliance, Ohio, a corporation of Ohio

Application March 20, 1947, Serial No. 735,858

2 Claims. (Cl. 126—298)

1

The invention relates to andiron construction for use at a fireplace front opening to provide from time to time a clearway in the space where a usual andiron front upright extends. This may be desirable on the one hand when the fireplace opening is protected by a screen having forwardly swinging hinged doors, or on the other hand when placing wood logs into the fireplace.

In usual andiron construction with a rigid upright front member, it is very difficult to place large pieces of wood or logs into the fireplace behind the front member, and when a screen has been used including hinged doors which may mount panes or slabs of heat resistant glass, it has been usual to place the andiron back of the door because the rigid upright front member of the andiron prevents the opening of the door when the rigid upright front member of the andiron is placed in front of the door.

Placing the andiron inside the fireplace between the glass in the door and the fire, results in the andiron becoming dirty with an accumulation of soot and smoke and also produces tarnish on the andiron.

The objects of the present invention include the provision of improved andiron construction which is operative to provide a clearway across the top of the top horizontal member of the andiron so as to permit the easy insertion of pieces of wood into the fireplace in which the andiron is used, and when used with a screen having outwardly swinging doors, which permits the placement of the andiron in front of the door, and the provision of the clearway when it is desired to swing the door outwardly.

Further objects of the present invention include the provision of such an improved andiron construction in which the parts are of simplified form and arrangement, and adapted for easy and economical manufacture.

The foregoing and other objects are attained by the andiron construction, parts, combinations, and sub-combinations which comprise the present invention and the nature of which is set forth in the following general statement, and preferred embodiments of which are set forth in the following description, and which are particularly and distinctly pointed out and set forth in the appended claims forming part hereof.

The nature of the improved andiron construction of the present invention may be stated in general terms as including a base having front and rear feet carrying an upper horizontal member. At the forward end of the horizontal member, a longitudinally extending front member has

2

at one end a pivotal connection with the horizontal member and extends longitudinally from the pivotal connection, whereby the front member is adapted to be swung about a horizontal axis between an upright position and a forwardly extending horizontal position substantially parallel with the horizontal member. Preferably spring catch means are provided for releasably maintaining the front member in the upright position.

10 By way of example, preferred embodiments of the improved andiron construction of the present invention and of improved parts thereof, are illustrated in the accompanying drawing forming part hereof, in which

15 Figure 1 is a front elevation of an andiron including the present improvements in combination with a fire screen shown in fragmentary front elevation, the fire screen having a forwardly swinging door, and the andiron front member being shown in its upright position;

Fig. 2 is a fragmentary elevation view thereof; and

Fig. 3 is a view similar to Fig. 2 in which the andiron front member is swung forwardly to the horizontal position.

Similar numerals refer to similar parts throughout the several views of the drawing.

The illustrated embodiment of the andiron, including the present improvements is indicated generally by 10, and is shown in combination with a fire screen indicated generally by 11, the fire screen including a rectangular frame indicated generally by 12 which extends across the front opening of a fireplace, not shown. The frame 12

35 has a horizontal bottom member 13 from each end of which extends upwardly a vertical side member 14. A door indicated generally by 15 is mounted for swinging forwardly by hinges 16 on each side member 14, and as shown the door 40 includes a door frame 17 in which is mounted a pane or slab 18 of heat resistant glass.

The improved andiron 10 includes a base indicated generally by 19 having sets of front and rear feet 20 and 21 which are spaced from each other and which support respectively the front and rear ends of an upper horizontal member 23.

The improved andiron 10 furthermore includes a normally vertically extending front member 24 having an end 25 located at the upper side of 50 the forward end 26 of the upper horizontal member 23 of the base 19 and provided with the depending feet 30 adapted to be located vertically against the back of the front feed 20 of the base when the front member 24 is in upright position, 55 as best shown in Fig. 2, and to be located hori-

zontally above the base when the front member 24 is swung into horizontal position as shown in Fig. 3.

Pivot hinge means indicated generally by 27 connect the end 25 of the andiron front member 24 with the end 26 of the andiron base upper member 23, the pivot means 27 having a pivot axis 28 which is perpendicular to a vertical plane extending through the upper horizontal andiron base member 23.

The andiron front member 24 is swingable between the upright position shown in Figs. 1 and 2 and the forwardly extending horizontal position shown in Fig. 3 which is substantially parallel with the upper horizontal andiron base member 23.

As shown, the rear feet 21 are abutted against the front face of the screen bottom member 13, and are preferably secured thereto. Spring catch means 29 are interposed between the front end 26 of the andiron base upper member 23 and the pivot connected end 25 of the andiron front member 24, and the spring catch means 29 serve to releasably retain the andiron front member 24 in its upright position as shown in Figs. 1 and 2, which is the position it occupies most of the time, providing the usual decorative effect of a usual rigid andiron.

When the andiron front member 24 is swung to its lowered horizontal position as shown in Fig. 3, clearway is provided for placing pieces of wood into the fireplace through the front opening thereof, and when the andiron 10 is combined as illustrated with the screen 11, clearway is also provided for permitting each door 15 to swing forwardly across the top of the andiron base 19 and the lowered andiron front member 24, which are below the door.

The embodiments of the present improvements illustrated and described herein are by way of example, and the scope of the present invention is not limited to the same or to the particular details thereof, but is commensurate with any and all novel subject matter contained herein which may at any time properly under the patent laws be set forth in the claims hereof or originating herein, and the elements of any such claims are intended to include their reasonable mechanical and functional equivalents.

I claim:

1. In andiron construction, a base, having spaced pairs of front and rear feet and an upper member extending between and supported on the feet, a normally vertically extending front member, the base upper member including a forward end, and the vertically extending front member including an end adjacent the base mem-

ber forward end, and pivot hinge means connecting the adjacent end of the front member with the forward end of the base upper member, the pivot means having a pivot axis perpendicular to a vertical plane passing through the base upper member, and the andiron front member being adapted to swing from an upright position to a lowered position substantially parallel with the base upper member, and a pair of feet connected to the normally vertically extending front member and extending oppositely therefrom beyond the pivot hinge and adapted to be located vertically against the back of said front feet of the base when the front member is swung to upright position and to be located horizontally above the upper member of the base when the front member is swung into lowered position.

2. In andiron construction, a base having spaced pairs of front and rear feet and an upper member extending between and supported on the feet, a normally vertically extending front member, the base upper member including a forward end, and the vertically extending front member including an end adjacent the base member forward end, and pivot hinge means connecting the adjacent end of the front member with the forward end of the base upper member, the pivot means having a pivot axis perpendicular to a vertical plane passing through the base upper member, and the andiron front member being adapted to swing from an upright position to a lowered position substantially parallel with the base upper member, and a pair of feet connected to the normally vertically extending front member and extending oppositely therefrom beyond the pivot hinge and adapted to be located vertically against the back of said front feet of the base when the front member is swung to upright position and to be located horizontally above the upper member of the base when the front member is swung into lowered position.

3. In andiron construction, a base having spaced pairs of front and rear feet and an upper member extending between and supported on the feet, a normally vertically extending front member, the base upper member including a forward end, and the vertically extending front member including an end adjacent the base mem-
